UNITED STATES PATENT OFFICE

2,627,896

SELF-OPERATED AIRPLANE SWING

Martin E. Walter, Clarinda, Iowa

Application June 6, 1946, Serial No. 674,863

5 Claims. (Cl. 155—65)

1

The principal object of this invention is to provide a swing of simple construction having the appearance of an airplane and capable of being operated solely by the user.

A further object of my invention is to provide an airplane swing that can be operated by either the hands or feet or by both the hands and feet in conjunction with one another, thereby providing excellent body exercise for the child or person using the device.

A still further object of this invention is to provide a swing that has a seat and horizontal rests for both hands and both feet, thereby providing a swing that is safe even for small children.

A still further object of my invention is to provide a swing that can be easily mounted or dismounted and with its operating mechanism so designed that there is no danger of injury to the user.

A further object of this invention is to provide a self-operated airplane swing that is economical in manufacture and durable in use.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a perspective view of my device in normal installed position.

Fig. 2 is a top plan view of the swing and more fully illustrates its construction.

Fig. 3 is a side view of the swing and more fully illustrates the method of operation.

Fig. 4 is a reduced side view of the swing illustrating its method of mounting.

Self-propelled swings are not new in the art, but most of such swings are either not attractive for the use of children, or are extremely complicated and in most instances provide objectionable operating mechanism capable of pinching or injuring the user. I have overcome such disadvantages as will hereinafter be explained.

Referring to the drawings, the numeral 10 designates an elongated board with its length extending horizontal and its width vertical. This member 10 is cut to represent the fuselage and vertical tail fin of an airplane. The numerals 11 and 12 designate horizontal stabilizers cut and secured to the tail portion of the member 10. The numeral 13 designates a horizontal board transversely secured to the top of the member 10, forward of its center, and forming the wing

2

portion of the swing. The numerals 14 and 15 designate circular cut-out portions in the forward leading edge of the wing 13, close to and adjacent the side planes of the member 10, as shown in Fig. 2.

The center portion of the top of the member 13 provides a seat for the user and the cut-away portions 14 and 15 permit the legs of the user to extend downwardly and forwardly. The numeral 16 designates a back board for the back of the user secured to the center trailing edge of the wing portion 13. This member 16 is semi-circular to give a rounded appearance to the fuselage. The numerals 17 and 18 designate two bars at each side of the forward portion of the member 10 and pivoted thereto near their centers by a pin 19. The numeral 20 designates a rod secured to and extending through the lower ends of the bars 17 and 18. This member 20 forms the rest for the two feet of the user. The numeral 21 designates an elongated rod secured to and extending through the upper end portions of the members 17 and 18, as shown in Fig. 1. The member 20 is positioned below the fuselage 10 and the member 21 is positioned above the fuselage 10. The fuselage 10 is so formed at its upper forward portion that from the seat portion 13 it extends forwardly and upwardly toward the tops of the members 17 and 18 and then downwardly and forwardly from the members 17 and 18. This portion of the member 10 is designated by the numeral 22 and not only gives a proper airplane appearance to the swing, but eliminates any possibility of the hands of the user getting pinched between the fuselage and the members 17 and 18 when the members 17 and 18 are reciprocated manually to operate the swing. This is an important feature of my invention inasmuch as not only children, but grown-ups can become severely injured if the upper forward end of the portion of the swing is not provided with the portion 22.

To support the swing, a chain, cable, or like 23 is secured by suitable means to the tail of the fuselage and to a supporting member 24. A similar flexible chain or like 25 is secured to the right outer end of the member 21 and the support 24. A like flexible chain or like 26 is secured to the outer left end of the member 21 and the supporting member 24. The numeral 27 designates a propeller rotatably secured to the nose of the fuselage. When the swing is used the swinging action of the device forward and back will cause this propeller to rotate. Blocks 28 may be secured at each side of the nose of the member 10 to simulate an engine.

After the device has been hung it is simple matter for a child to climb upon it and mount it inasmuch as the device is stable with three points of suspension and with the member 29 capable of being used as a step. Once a child has mounted the swing there is no danger of his accidentally falling off, as the fuselage 10 is between his legs, the member 20 under his feet, the cut-away portions 14 and 15 embracing the upper portions of his legs, with the member 16 preventing his sliding rearwardly on the device, and with the member 21 supporting his hands. To operate the device the user may pull and push the rod bar 21, or he can reciprocate the foot bar 20, or he can operate the members 21 and 20 with both hands and feet simultaneously, thereby causing the swing to move forwardly and rearwardly.

From the foregoing, it will be seen that I have provided a swing of unique design and construction and one that is simple to manufacture and safe to use.

Some changes may be made in the construction and arrangement of my improved self-operated airplane swing without departing from the real spirit and purpose of my invention, and it is my intention to cover by my claims any modified forms of structure or use of mechanical equivalents which may be reasonably included within their scope.

I claim:

1. In a device of the class described, an elongated flat member having its width vertical, a flat elongated member having its width substantially horizontal, secured at its center to the upper central portion of the first-mentioned elongated member and simulating the wings of an airplane, two bar members at each side of the forward portion of said first-mentioned elongated member and having their center portions pivoted thereto, a foot bar secured to the lower end portions of said two bar members, a hand bar secured to the upper end portions of said two bar members, a elongated flexible supporting member secured to the rear end portion of said first-mentioned elongated member, and two elongated flexible supporting members spaced apart from each other and secured to said hand bar; said first-mentioned elongated member having its upper forward end portion extending first upwardly and forwardly toward the upper end portions of said two bar members to a point vertically aligned above the pivot point of said two bar members and then immediately downwardly and forwardly from the upper end portions of said two bar members.

2. In a device of the class described, an elongated flat member having its width vertical, a flat elongated member having its width substantially horizontal, secured at its center to the upper central portion of the first-mentioned elongated member and simulating the wings of an airplane, two bar members at each side of the forward portion of said first-mentioned elongated member and having their center portions pivoted thereto, a foot bar secured to the lower end portions of said two bar members, a hand bar secured to the upper end portions of said two bar members, an elongated flexible supporting member secured to the rear end portion of said first-mentioned elongated member, two elongated flexible supporting members spaced apart from each other and secured to said hand bar; said first-mentioned elongated member having its upper forward end portion extending first upward-

ly and forwardly toward the upper end portions of said two bar members to a point vertically aligned above the pivot point of said two bar members and then immediately downwardly and forwardly from the upper end portions of said two bar members, and a seat back secured to the rear central top of said second-mentioned elongated flat member.

3. In a device of the class described, an elongated flat member having its width vertical, a flat elongated member having its width substantially horizontal, secured at its center to the upper central portion of the first-mentioned elongated member and simulating the wings of an airplane, two bar members at each side of the forward portion of said first-mentioned elongated member and having their center portions pivoted thereto, a foot bar secured to the lower end portions of said two bar members, a hand bar secured to the upper end portions of said two bar members, an elongated flexible supporting member secured to the rear end portion of said first-mentioned elongated member, two elongated flexible supporting members spaced apart from each other and secured to said hand bar; said first-mentioned elongated member having its upper forward end portion extending first upwardly and forwardly toward the upper end portions of said two bar members to a point vertically aligned above the pivot point of said two bar members and then immediately downwardly and forwardly from the upper end portions of said two bar members, a seat back secured to the rear central top of said second-mentioned elongated flat member, and two cut-away portions in the central leading edge portion of said second-mentioned elongated flat member.

4. In a device of the class described, an elongated flat member having its width vertical, a flat elongated member having its width substantially horizontal, secured at its center to the upper central portion of the first-mentioned elongated member and simulating the wings of an airplane, two bar members at each side of the forward portion of said first-mentioned elongated member and having their center portions pivoted thereto, a foot bar secured to the lower end portions of said two bar members, a hand bar secured to the upper end portions of said two bar members, an elongated flexible supporting member secured to the rear end portion of said first-mentioned elongated member, two elongated flexible supporting members spaced apart from each other and secured to said hand bar; said first-mentioned elongated member having its upper forward end portion extending first upwardly and forwardly toward the upper end portions of said two bar members to a point vertically aligned above the pivot point of said two bar members and then immediately downwardly and forwardly from the upper end portions of said two bar members, a seat back secured to the rear central top of said second-mentioned elongated flat member, two cut-away portions in the central leading edge portion of said second-mentioned elongated flat member, and a propeller rotatably mounted on the forward end of said first-mentioned elongated flat member.

5. In a device of the class described, an elongated flat member having its width vertical, a flat elongated member having its width substantially horizontal, secured at its center to the upper central portion of the first-mentioned elongated member and simulating the wings of an airplane, two bar members at each side of the forward por-

tion of said first-mentioned elongated member and having their center portions pivoted thereto, a foot bar secured to the lower end portions of said two bar members, a hand bar secured to the upper end portions of said two bar members, an elongated flexible supporting member secured to the rear end portion of said first-mentioned elongated member, two elongated flexible supporting members spaced apart from each other and secured to said hand bar; said first-mentioned elongated member having its upper forward end portion extending first upwardly and forwardly toward the upper end portions of said two bar members to a point vertically aligned above the pivot point of said two bar members and then immediately downwardly and forwardly from the upper end portions of said two bar members, a seat back secured to the rear central top of said second-mentioned elongated flat member, two cut-away portions in the central leading edge 20

portion of said second-mentioned elongated flat member, a propeller rotatably mounted on the forward end of said first-mentioned elongated flat member, and substantially horizontally extending members at each side of the rear end portion of said first-mentioned elongated flat member.
